(57) **CLAIM**

The ornamental design for a stackable popcorn lid having detents, and bowl combination, as shown and described.

DESCRIPTION

FIG. 1 is a front perspective view of the stackable popcorn lid having detents, and bowl combination.

FIG. 2 is a top view thereof;

FIG. 3 is a bottom view thereof;

FIG. 4 is a right side view in a first position of use, the left being a mirror image thereof; and,

FIG. 5 is a right side view in a second position of use, the left being a mirror image thereof.

The broken lines showing the popcorn bucket are included for environmental purposes only and form no part of the claim.
